UNITED STATES PATENT OFFICE

134,040

DESIGN FOR A CHAIR

Henry Peter Glass, Chicago, Ill., assignor to W. L. Stensgaard & Associates, Inc., a corporation of Illinois

Application July 22, 1942, Serial No. 107,649

Term of patent 14 years

To all whom it may concern:

Be it known that I, Henry Peter Glass, formerly a citizen of Austria (having obtained my first citizenship papers in the United States, but not yet being a naturalized citizen of the United States), residing at Chicago, in the county of Cook and State of Illinois, have invented a new, original, and ornamental Design for a Chair, of which the following is a specification, reference being had to the accompanying drawing, forming a part thereof, in which:

Figure 1 is a front elevational view of the chair, showing my new design; Figure 2 is a side elevational view; Figure 3 is a top plan view; and Figure 4 is a rear elevational view thereof.

I claim:

The ornamental design for a chair, as shown.

HENRY PETER GLASS.
